UNITED STATES PATENT OFFICE.

PHILIP DIEHL AND ALFRED GRIEB, OF ELIZABETH, NEW JERSEY, ASSIGNORS
TO THE SINGER MANUFACTURING COMPANY, OF NEW JERSEY.

CIRCULARLY-MOVING-HOOK SEWING-MACHINE.

SPECIFICATION forming part of Letters Patent No. 678,947, dated July 23, 1901.

Original application filed April 9, 1900, Serial No. 12,215. Divided and this application filed October 16, 1900. Serial No. 33,211. (No model.)

To all whom it may concern:

Be it known that we, PHILIP DIEHL and ALFRED GRIEB, citizens of the United States, residing at Elizabeth, in the county of Union 5 and State of New Jersey, have invented certain new and useful Improvements in Sewing-Machines, of which the following is a specification, reference being had therein to the accompanying drawings.

- 10 This invention relates to that class of lock-stitch sewing-machines in which the loops of needle-thread are carried by a circularly-moving oscillating or rotating hook around a stationary thread-case supported by said 15 hook, so that said thread-case does not have to be lifted by the loops of needle-thread in passing beneath it, thus allowing the needle-thread to pass around the thread-case with the least possible friction or drag on said 20 needle-thread. In the present case the loop-taking hook is disposed horizontally, so as to move circularly in a horizontal plane, and is preferably given an oscillating movement, the loop-seizing beak or hook proper being 25 formed on the inner face of the hook ring or segment by which the thread-case is supported and said thread-case being preferably eccentric to and, in fact, mainly to one side of the line of the axis of movement of the hook, 30 so that the loops of needle-thread are carried around the thread-case to discharging position by a comparatively short circular movement of the hook.

The present invention relates to some of the 35 details of construction of the machine shown and described in our application, Serial No. 12,215, filed April 9, 1900, of which application this case is a division.

In the accompanying drawings, Figure 1 is 40 a sectional side view of a machine embodying the invention, and Fig. 2 is a bottom view thereof. Fig. 3 is a cross-section of the lower part of the machine on line 3 3, Fig. 2, looking in the direction of the arrow adjacent to 45 said line. Fig. 4 is a detail plan view showing the circularly-moving hook, the thread-case, and the holder for maintaining the latter stationary. Fig. 5 is a detail plan view of the hook with the thread-case omitted and 50 the holder removed from its supporting-

bracket. Fig. 6 is a detail plan view of the thread-case. Fig. 7 is a cross-section of the thread-case and also of the bobbin, this view showing also the thread-case holder partly in elevation and partly in section on line 7 7, 55 Fig. 10. Fig. 8 is a detail view to show the operative relation of the thread-case and hook, the latter being in cross-section; and Fig. 9 is a similar view, but showing also the hook-shaft-supporting bracket as seen looking 60 from the right of Fig. 4, with the hook-ring in section on line 9 9 and the bracket in section on line 10 10, Fig. 4, this view showing also the thread-case holder in elevation. Fig. 10 is a detail plan view of the thread-case 65 holder, and Fig. 11 is a detail bottom view of the thread-case.

Referring to the drawings, *a* denotes the arm of the machine; *b*, the bed-plate; *c*, the horizontal driving-shaft, journaled in the upper portion of said arm and provided near its rear end with a crank *d* and having at its forward end a crank *e*, connected by a pitman *f* with the needle-bar *g*, carrying the usual eye-pointed needle *h*, said crank *e* being also connected in a well-known manner with the "link" take-up *i*. The crank *d* is embraced by a fork at the upper end of a vertical rock-shaft *j*, having at its lower end an arm *k*, connected by a pitman *l* to an arm *m* 70 of a rocking hub *n*, provided with a grooved cam *o*, and having a second arm *p*, joined by a link *q* to an arm *r* of the rocking hook-shafts.

The feed-bar *t* is reciprocated horizontally, as is common in a well-known style of 85 "Singer" feeding mechanism, by a rocking feed-shaft *u*, having at its rear end an arm *v*, to which is jointed the lower end of a feed connection or link *l*, operated from a cam or eccentric *w* on the driving-shaft *c*. The vertical movements of the feed-bar are imparted thereto from the grooved cam *o* in the rocking hub or sleeve *n*, journaled on the fixed pin or stud *x*, the groove of said cam being entered by a roller-stud *y* on a lever *z*, pivoted at 2 to the bracket *3*, depending from the work-plate and forked or slotted at its free end to embrace a roller-stud *4*, with which the feed-bar *t* is provided.

The hook-shafts carries at its upper end a 90 95 100

horizontally-disposed circularly-moving hook or hook-ring 5, connected with said shaft by one or more webs or spokes 6, said hook-ring having an inwardly-extending rib or flange 7, 5 on the inner face of which is formed the loop-seizing beak or hook proper, 8, outside of which is a throat 9, in which the loops of needle-thread are carried around, the thread-case 10 having a peripheral groove 11 entered by the 10 said rib or flange 7 to enable the said thread-case to be entirely supported by the said hook-ring or hook, owing to the rib-and-groove connection of these parts. The thread-case is 15 preferably furnished with a bobbin 12 to contain the lower or locking thread; but it is obvious that a cop of thread might be used instead of the bobbin, if desired.

The thread-case 10 is preferably arranged eccentric to and, in fact, so as to have its 20 thread-chamber or bobbin-chamber mainly to one side of the axis of movement of the circularly-moving hook. The eccentrically-arranged thread-case is on that side of the axis of the hook toward which the loops of needle-thread are first carried by the beak of the hook in spreading the loops of needle-thread around the thread-case, or, in other words, the said thread-case is eccentric to the axis of the hook toward that side of the circular 25 path of the hook first traversed by the beak of the hook after said beak has taken a loop of needle-thread from the needle. This eccentric arrangement of the thread-case relative to the hook-ring or hook by which it is 30 supported permits of an early cast-off in the movements of the hook of the loops of needle-thread over the thread-case, so that shorter circular movements of the hook than have heretofore been required to secure this cast- 35 off may be employed, thereby lessening friction, so as to consume less power and contributing to higher speed than heretofore, as also affording more time in the rotation of the driving-shaft for the easy and proper action of the feed and take-up.

Attached to the bracket 3 and arranged within the hook-ring is a holder 13, which serves to maintain the thread-case stationary as the hook-ring travels about it. The thread-case is not in contact with the said holder excepting at or near the opposite ends or horns of the latter and against one or the other of which parts the said thread-case will at times rest lightly. These points of contact between 50 the holder and thread-case are respectively near the loop-dividing portion 14 and the loop-discharging or heel portion 15 of the said thread-case, the last-named point of contact of the holder and thread-case being preferably 55 afforded by a small pin 16, having a rounded end for contact with the thread-case, the said pin being yieldingly mounted by reason of a small spring 17, which presses lightly against its opposite end, so that the said contact-pin 60 may yield a little, if necessary, to allow the needle-loops to pass easily. The yielding contact afforded by the said spring-pressed pin

16 also serves to lessen or deaden any noise which might be occasioned by contact of the parts in the operation of the machine, or, in 70 other words, the said yielding contact serves as a muffler.

The oscillating movements of the loop-taker or hook 5 may be and preferably are so timed that when a loop of needle-thread is passing 75 over the cast-off or loop-discharging portion of the thread-case the hook will have commenced its reverse movement, so that the light frictional contact between the hook and thread-case will tend to open a free thread- 80 passage between the heel portion of said case and the contact-pin 16, and when the shortening loop is passing the loop-dividing portion of the thread-case the forward movement of the hook at that time will have a tendency 85 to open a free thread-passage between the said loop-dividing portion of said thread-case and the contact portion of the holder adjacent thereto, and thus the loops of needle-thread will be carried around the thread-case 90 with the least possible friction or strain on said needle-thread.

The holder 13 is preferably provided with a needle-guard 18 to guide the vertically-reciprocating needle *h* and keep it out of the 95 way of the advancing beak 8 of the horizontally-moving hook, and the said holder is also preferably provided with a loop-guard 19, which extends out over the flange 7 of the hook-ring adjacent to the loop-discharging 100 portion of the thread-case and which serves to prevent the loops of needle-thread from catching on the said holder. A second loop-guard afforded by the arm 20, attached to the 105 holder, serves to steady the loops of needle-thread after they have been carried around the thread-case and prevent them from flopping or kinking when being drawn up by the take-up and as they are passing between the thread-case 10 and the holder. The thread-case holder 13 is also preferably provided with a small bobbin-ejecting lever 21, one arm of 110 which extends beneath the bobbin, resting on an annular lip or flange at the bottom of the bobbin-chamber at the thread-case, and the 115 other or upper arm of which is constructed and arranged to afford a finger-piece to be pressed upon by the attendant and to thus lift the bobbin from its seat in the thread-case, thus facilitating the removal of the said 120 bobbin from said case. The bobbin-ejecting lever 21 is pivoted on the screw 22 and is held in its normal or inoperative position (shown in Fig. 7) by a small coil-spring 23, interposed between said lever and the portion 24 125 of the said holder.

In the operation of the machine above described the vertically-reciprocating needle *h* descends within the circularly-moving loop-taker or hook-ring 5, and as the needle rises 130 and throws out its loop the latter is caught by the beak 8 and is carried in the throat 9 of the hook against the loop-dividing portion 14 of the thread-case 10. As the hook now con-

tinues its forward movement, with the needle-thread held in the said throat 9 of the said hook, one limb of the loop passes freely around beneath the thread-case supported on 5 the flange or rib 7 of the hook and clear of the web or webs connecting the hook ring or segment with the hook-shaft *s*, and the other limb of the said loop passes freely over the top of the thread-case. The bight of the loop 10 of needle-thread carried in the throat 9 of the hook passes freely around the periphery of the thread-case and after having been carried to the cast-off portion of said case can in being tightened by the take-up be readily drawn 15 through between the thread-case and its holder, as hereinbefore described, and thus the loops of needle-thread are carried entirely around the thread-case with a minimum of friction on said thread. For this reason 20 the lightest and finest needle-threads may be used with machines running at the highest speeds with little or no danger of breakage of the thread. This improved machine, in which the eccentrically-arranged thread-case 25 is supported by the circularly-moving horizontally-disposed loop taker or hook, presents very great advantages over machines in the prior art, in which the thread-cases were not supported by the hooks and had therefore to 30 be lifted by the thread each time a loop of needle-thread was passed around the thread-cases, as in machines of the kind just referred to the friction on the needle-thread in passing around the thread-cases was so great that 35 high speeds were impossible without endangering breakage of the needle-thread. This improved machine, with its eccentrically-arranged thread-case supported by the hook, also possesses great advantages over machines 40 known to the prior art in which the thread-cases were supported by the hooks, but were not so arranged, as is the thread-case of the present machine, as to secure an early discharge of the loops of needle-thread about the 45 thread-cases, for the reason that the present invention obviates the necessity of the differential or irregular movements or double rotations of the hooks heretofore employed in order to secure sufficient time in the rotation 50 of the driving-shaft for a proper operation of the feed and take-up.

We do not herein claim, broadly, the in-

vention above described, and illustrated in the accompanying drawings, as the same is embraced by our application, Serial No. 12,215, 55 filed April 9, 1900; but

What we do herein claim, and desire to secure by Letters Patent, is—

1. In a sewing-machine, the combination with a driving-shaft in the upper portion of 60 the arm thereof, a needle-bar operatively connected with the forward end of said shaft, a vertical rock-shaft in the vertical portion of said arm and operatively connected with said driving-shaft, a vertical rocking hub or 65 rocker connected with said vertical rock-shaft, a vertical rock-shaft at the forward end of the machine operatively connected with said rocker, an oscillating loop-taking hook operated by said last-named rock-shaft 70 and coöperating with the needle carried by said needle-bar in forming stitches, and a stationary thread-case supported by said loop-taking hook and arranged eccentric to the axis of the latter on that side of said axis 75 toward which the loops of needle-thread are first carried by the said hook in spreading said loops over said thread-case.

2. The combination with the driving-shaft *c*, of the needle-bar operatively connected 80 with the forward end of said shaft, the rock-shaft *j* connected with the said driving-shaft the vertical rocking hub or rocker *n* having the arms *m* and *p*, the pitman *l* connecting said rock-shaft *j* with the said arm *m* of said 85 rocking hub, the rock-shaft *s* operatively connected with the said arm *p* of said rocking hub and provided with a loop-taking hook coöperating with the needle carried by said needle-bar in the formation of stitches, and 90 a stationary thread-case supported by said hook and arranged eccentric to the axis of the latter on that side of said axis toward which the loops of needle-thread are first carried by the said hook in spreading said loops 95 over said thread-case.

In testimony whereof we affix our signatures in the presence of two witnesses.

PHILIP DIEHL.
ALFRED GRIEB.
